HEAD MOTION FOR LOOMS

Application filed December 22, 1930. Serial No. 503,919.

This invention relates to improvements in head motions for looms and it is the general object of the invention to improve the construction and operation of the so-called lock knife for the vibrator levers of a Knowles loom.

The so-called Knowles loom employs a harness mechanism provided with two spaced continuously rotating mutilated cylinder gears between which lie a series of vibrator levers the position of which is determined by a pattern chain. When the vibrator lever is raised by the chain it engages the top cylinder and any tendency of the vibrator gear 5 to move out of mesh with it is resisted by the chain. When the vibrator gear is in mesh with the lower cylinder, however, the upward thrust from that cylinder cannot be resisted by the chain and it is necessary to provide some form of lock to hold the levers when they are in down position. Inasmuch as certain vibrators are up and others are down on each pick of the loom it is necessary to apply the lock on every loom beat. When 15 making a pick-out to correct a mispick the sequence of movements of the harnesses for the immediately preceding picks must be reversed and this is conveniently accomplished by means of a reverse gearing interposed between the bottom cylinder and the drive for 20 the pattern chain cylinder.

As heretofore made the lock knife has been actuated from a cam mounted on the shaft of the lower cylinder but because of the proximity of the latter to the reverse gearing there has been very little room for the cam and the latter had consequently been made very small. Also, in previous constructions, the arm which engages the cam was mounted 35 directly on the shaft to which the lock knife supporting arms were secured and the only means of varying the amount of movement of the lock knife was to vary the length of the cam engaging arm. In view of the fact, 40 however, that the distance between the centers of the lower cylinder and the rod for the cam remained fixed this adjustment also varied the time of movement of the lock knife with respect to the angular position of the cylinders.

It is an important object of my present

invention to provide a control for the lock knife including a lever which has always the same amount of angular movement and to introduce connections between this lever and the lock knife proper, whereby the latter may be given as much movement of the lever as is desired. In this connection it is also desirable to adjust the angular position of the cam with respect to the cylinder gears so as to vary the time relation between the lock knife and the movements of the vibrator levers. These results I accomplish by placing the cam on the shaft of the top cylinder which is sufficiently removed from the reverse gearing to permit the use of an intermediate connector, and also permits the use of a larger cam which has increased wearing properties.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a front elevation of a head having my invention applied thereto,

Fig. 2 is a partial detail plan view taken in the direction of arrow 2, Fig. 1,

Fig. 3 is a detailed vertical section on line 3—3 of Fig. 2, and

Fig. 4 is a vertical section on line 4—4 of Fig. 3.

Referring to Fig. 1, I have shown a loom arch or head frame 10 in which is mounted for rotation in opposite directions upper and lower mutilated cylinder gears 11 and 12, respectively. A fixed heel pin 13 provides pivotal support for vibrator levers 14. The position of the latter is determined by the pattern mechanism 15 which is driven by appropriate connection not shown from the lower cylinder. A reverse gearing designated generally at 16 includes a stud 17 which is at substantially the same distance from the shaft 18 of the pattern cylinder as is the axis of the lower cylinder 12. The purpose of this relation is to permit meshing of the pattern cylinder driving gear not shown with the reverse gearing.

Each vibrator lever has rotatably mounted thereon a vibrator gear 19 attached to a connector 20 the right hand end of which as set forth in Fig. 1 may be connected to a harness 5 jack or lever 21. The vibrator levers have their inner or right ends as shown in Fig. 1 extended through a guide comb 22 fixed with respect to the loom frame. A lock knife 23 extends in a direction parallel to the axis of 10 the cylinders and has a left hand edge to cooperate with the reduced portions of the vibrator gears which extend to the right of the comb 22. The lock knife may be mounted on a pair of arms 24 adjustably connected 15 longitudinally and angularly on a rock pin 25.

In operation, the pattern chain will rotate so as to present a different bar under the vibrator levers each pick of the loom so as 20 to determine the relation of the various vibrator gears with respect to the cylinders. Just prior to the engagement of the cylinders with the vibrator gears the lock knife 23 is moved to the position shown in Fig. 1 so as to prevent 25 improper vertical movement of the levers. A coil spring 26 may be interposed between the lock knife frame and a fixed part of the loom and holds the lock knife yielding 30 in locking position with respect to the levers.

The matter thus far described forms no part of my present invention and is the well known Knowles head.

In carrying my improvements into effect I 35 secure a short arm 40 to rock pin 25 by means of a set screw 41 which enables the angular relation of the arm to be varied with respect to the lock knife frame. Pivotal connected to and extending upwardly from the arm 40 is a link or rod 42 the upper end of which is connected by means of a stud 43 to another lever 44. A slot 45 in this last named lever affords adjustment for the stud 43 toward and from the pivotal mounting 46, the latter being fixed with respect to the loom frame.

The free end of the lever 44 has rotatably mounted therein an anti-friction roller 47 which lies over a cam 48. The latter is secured by means of two set screws 49 to the shaft 50 forming part of the top cylinder 11. The usual hand wheel 51 may have its hub 52 closely adjacent the cam 48. The cam has low and high dwells 53 and 54, respectively, which are connected by inclined surfaces 55.

In operation, continued rotation of the top shaft will cause the cam to rock the lever 44 periodically in a vertical plane. By means of link 42 the arm 40 and therefore the lock knife will move in timed relation with the 60 movements of the cylinders. It is to be understood that both cylinders are geared together and perform a complete operation in the same period of timing.

The lever 44 will always rise at precisely the same time with respect to the position of

the top cylinder regardless of the position of the stud 43, so long as cam 48 remains unchanged. Likewise, if it be desired to change the cam so that the time of the movement of the lock knife may be varied with respect to the rotary movement of the cylinders, such an adjustment can be made without varying the extent of movement of the lock knife.

From the foregoing it will be seen that I 75 have provided a control for the lock knife of a Knowles loom so arranged that the amount of movement of the lock knife and the time of its movement with respect to the time of the head can be varied independently of each other. Furthermore, the cam can be made larger than those heretofore employed because of the fact that it is on the top shaft and removed from the reversing mechanism 16.

Having thus described my invention it will be seen that changes and modifications may be made therein by those skilled in the art without departing from the spirit and scope of the invention and I do not wish to be limited to the details herein disclosed, but what I claim is:

1. In a head motion for looms having upper and lower actuating cylinders and a reverse gearing connected with the lower cylinder together with vibrator levers between the cylinders, a cam rotating with the upper cylinder, a lever having regular movements derived from the cam, a second lever, connections between the levers, and a lock knife operatively connected to the second lever and movable regularly in timed relation to the cylinders to lock the vibrator levers.

2. In a head motion for looms, upper and lower rotating actuator cylinders geared together, a cam rotating with one cylinder, a lever deriving movements regularly from the cam, reverse gearing connected to the other cylinder, a second lever, a link between the levers connected adjustably to one of the levers, and a lock knife connected to the second lever and movable in timed relation and regularly with respect to the actuator cylinder.

3. In a head motion for looms, upper and lower oppositely rotating actuator cylinders geared together, a cam rotating with one cylinder, a lever deriving movements regularly from the cam, reverse gearing connected to the other cylinder, a second lever, a link between the levers connected adjustably to one of the levers, and a lock knife connected to the second lever and movable in timed relation and regularly with respect to the actuator cylinder, the cam normally fixed relatively to the actuator cylinder but capable of assuming any one of a plurality of angular positions relatively thereto.

4. In a loom head motion having upper and lower rotating actuators geared together

with a vibrator lever located between them, a locking device for the lever, reverse gearing connected to one actuator, means rotating with the other actuator to vary the time of movement of the lock knife with respect to the rotative position of the actuators, and mechanism independent of said means to vary the extent of movement of the lock knife.

5. In a loom head motion having upper and lower oppositely rotating actuators with a vibrator lever located between them, a locking device for the lever, reverse gearing connected to one actuator, means rotating with the other actuator to vary the time of movement of the lock knife with respect to the rotative position of the actuators, and means to maintain the same degree of movement of the lock knife irrespective of the said time relation.

10 6. In a loom head motion having upper and lower oppositely rotating actuators, a cylinder and vibrator lever to cooperate therewith, a lock device for the lever, reverse gearing connected to one cylinder and means moving with the other cylinder to vary the extent and also the time of movement of the locking device, the extent of the movement being independent of the time of the movement.

15 7. In a loom head motion having a rotating actuator cylinder and vibrator lever to cooperate therewith, a lock device for the lever, a cam movable with the cylinder, a pivoted lever to cooperate with the cam and move therewith as the cylinder rotates, a link capable of attachment to the pivoted lever at any one of a plurality of positions relatively to the pivot of the lever, and a lever interposed between the link and the lock device to 20 transmit movement to the latter derived from the link, the time of movement of the first named lever being independent of the extent of movement of the link.

25 8. In a head motion for looms having upper and lower oppositely rotating actuator cylinders geared together and a vibrator lever located between the gear, a lock knife for the vibrator lever, a supporting lever for the lock knife pivoted adjacent the axis of one of the cylinders, reverse mechanism carried by the said one cylinder, a cam carried by the other cylinder and operating connections between the cam and the supporting lever to 30 rock the latter periodically as the cylinders rotate.

35 In testimony whereof I have hereunto affixed my signature.

WILLIAM M. WATTIE.
